DOLL'S HEAD

William C. Peterson, 31 Water St., Claremont, N.H.

Filed June 24, 1965, Ser. No. 85,877

Term of patent 3½ years

(Cl. D34—4)

FIG. 2

I claim:

The ornamental design for a doll's head, as shown.
